MECHANISM FOR FEEDING AND INKING
TYPEWRITER RIBBONSGeorge S. Brodd, Chicago, Ill., assignor to Ross J.
Beatty, Chicago, Ill.

Application November 22, 1933, Serial No. 699,191

6 Claims. (Cl. 197—171)

My present invention relates to improvements in a mechanism for feeding and inking a typewriter ribbon. I have illustrated my invention in conjunction with a manifolding attachment 5 for a typewriter employing an inked ribbon, which attachment is similar in many respects to the structure illustrated and described in the application for United States Letters Patent of Harold Thomas Mosfelt and Harold Schagerholm 10 for an improvement in "Manifolding apparatus", filed February 20, 1933, Serial No. 657,534, now Patent Number 1,942,722, issued January 9, 1934.

I conceived that certain important advantages could be obtained by or through the employment 15 of a plastic, as distinguished from a gravity feeding ink, in the inking of typewriter ribbons and as the structure of the above referred to application was not adapted to the employment of a plastic, as distinguished from a gravity feeding 20 ink, I developed the mechanism hereinafter illustrated and described in which I have not only provided instrumentalities for feeding a plastic ink but I have also somewhat simplified the mechanism for feeding the ribbon and have further provided a dependable mechanical mechanism 25 for controlling the amount of ink fed.

In the accompanying drawings—

Fig. 1 is a top plan of a manifolding attachment for a typewriter with which my invention 30 is associated.

Fig. 2 is a front elevation of the structure shown in Fig. 1.

Fig. 3 is an end view of the structures shown in Figs. 1 and 2 looking to the left.

Fig. 4 is a view of the opposite side of the structure shown in Fig. 3.

Fig. 5 is a section, to an enlarged scale, on line 5—5 of Fig. 6.

Fig. 6 is a section on line 6—6 of Fig. 5, and

Fig. 7 is a section on line 7—7 of Fig. 6.

Similar reference characters refer to similar parts throughout the respective views.

The manifolding apparatus with which my present invention is associated consists of a rectangular frame comprising a rear longitudinal rod 10 and a front bar 11 held in spaced relation by adjustable end members 12 and 13. From the rear portions of the end frame members 12 and 13 are developed bifurcated or slotted brackets 14 which engage portions of the conventional platen carriage of the typewriter. Upon the right hand portion of the front frame bar 11 is slidably mounted a spring pressed ribbon holding and tensioning arm 14a, outside of which and laying

parallel therewith is a stationary shield holding arm 15 also secured to the bar 11.

As will be seen most clearly in Fig. 3, a portion of the end frame member 13 consists of a casing 16 in and upon which is mounted the ribbon feeding and inking mechanism. To the bottom of the casing 16 is rigidly secured a ribbon guide arm 17 and a similar ribbon guide arm 18 is secured to and carried by a lever arm 19 pivoted at 20 to a portion of the casing 16. The ribbon guide arms 17 and 18 both have the elevational outline best seen in Fig. 2 so that there is provided in the ends of the ribbon guide arms 17 and 18 an angular recess through which the inked ribbon extending longitudinally across the front 15 of the frame to the tensioning arm 14a is turned at right angles so as to enter and emerge from the casing 16. The depending arm 18a upon the outside of the angular recess is employed to hold, in co-operation with the fixed arm 15, a ribbon shield 20 when such a ribbon shield is desired. Instead of carrying the ribbon, after it enters the casing 16, around the large roller to which ink is fed, as is done in the application heretofore referred to, I carry the ribbon, as most clearly 25 shown in Figs. 5 and 7, around a relatively small roller 21 which rotates upon a shaft 22 fixedly secured to the free end of an arm 23, the opposite end of which is pivoted upon a stud bolt 24 projecting from the side wall of the casing 16. In 30 the rear end of the casing 16 and in contact with the outer wall thereof is an ink reservoir 25 provided with a filler opening on the top thereof closed by a screw plug 26. The front vertical wall of the ink reservoir 25 has a semi-circular 35 or arcuate recess or depression 27 formed therein into which depression is fitted a surface layer of felting 28. In the arcuate depression in the wall of the ink reservoir is an aperture 29 and opposite to the aperture 29 the felting 28 is punctured 40 so as to permit the passage therethrough of the lower turned end of the feed bar 30. The consistency of the plastic ink which I employ is such that it will not pass by gravity or capillarity 45 through the puncture in the felting 28 opposite the aperture 29 in the wall of the ink reservoir but the plastic ink is nevertheless of such a viscous nature that minute quantities thereof adhere to the feeding bar 30 as it is thrust through the perforation in the felting and it adheres to a roller 50 31 as it is brought in contact therewith by means of the feed bar 30. The felting 28 against which the periphery of the roller 31 has light contact assists in uniformly distributing the ink upon the surface of the roller 31. 55

To drive the ribbon feeding and inking rollers 21 and 31 I employ a slide 32 secured by means of headed pins 33 to the inside face of the outer wall of the casing 16. The slide 32 has cut in 5 the portion of its upper edge a rack 34 which meshes with a gear 35 fixed to a ratchet 36. Upon the outer end of the inking wheel 31 is fixedly secured a gear 37 to which is pivoted a dog or detent 38 so that when the slide 32 is 10 forced into the casing 16 the gear 35 will be rotated together with the ratchet 36 fixedly secured thereto and the rotation of the ratchet 36 through the action of the pawl 38 will cause the 15 rotation of the gear 37, but when the slide 32 is projected from the casing by the action of the spring 39 the ratchet 36 will pass under the pawl 38 without rotating the gear 37. Upon the 20 end of the roller 21 around which the ribbon passes is secured a gear 40 which meshes with the gear 37 so as to rotate the rollers 21 and 31 simultaneously in opposite directions, which, together with the fact that the pull of the ribbon swings the roller 21 about the pivot 24 as a center toward the roller 31 and increases the 25 grip of the rollers as the tension on the ribbon increases.

Upon the slide 32, to the rear of the rack 34, is provided an integral upstanding dog or detent 41 which, when the slide 34 is pressed into 30 the casing 16, engages the depending end of the portion of the ink feed bar 30 which extends outside of the ink reservoir so as to retract the inner laterally turned end of the feed bar 30 from the perforation in the felting 28. The 35 shape and disposition of the ink feed bar 30 is best seen in Figs. 5, 6 and 7.

It will be seen from Fig. 6 that the feed bar is of a substantially U-shaped form and that while the arms of the U move in parallel planes, 40 when viewed transversely of these planes, as shown in Fig. 7, the arms form an angle with one another. The depending end of the inner arm is bent laterally to pass through the aperture 29 in the recessed ink reservoir well 27 and 45 the perforation in the felt layer 28. The portion of the U which joins the arms thereof passes through an aperture above the ink level in the ink reservoir and has fixedly secured thereto a disk 42 over which is carried a spring 43, one 50 end of which is secured to the externally depending arm of the ink feed bar 30 and the other end whereof is secured by a nut 44 to the adjacent wall of the ink reservoir 25. When the slide 32 is projected from the casing 16 through 55 the action of the spring 39 the exterior depending end of the ink feed bar which the projection or detent 41 has forced rearwardly, is permitted to move forwardly again under the action of the spring 43 which movement carries a quantity of 60 the viscid plastic ink on the inner turned end of the ink feed bar through the aperture 29 and through the perforation in the layer of felt 28 into contact with the roller 31. This happens each time the slide 32 is moved which is actuated by the line shift lever of the typewriter (not shown). The amount of ink adhering to 65 the inner laterally turned end of the ink feed bar, and thus applied to the periphery of the roller 31, depends to a considerable extent upon 70 the distance the feed bar travels through the plastic ink. To regulate this distance I rotatably mount upon the inner face of the wall of the casing 16 a disk 45 having a lug or projection 75 extending from an eccentric point in the disk 45 across the path of the exterior arm of the

ink feed bar 30. The shaft upon which the disk 45 is mounted extends through the wall of the casing 16 and upon the outside thereof is provided with an arm 47, by the rotation of which the extent of travel of the ink feed arm 30 may be controlled. I have made the arm 47 of spring material and the unattached end thereof is provided with a pin 48, the outer portion of which constitutes a manipulating handle and the inner portion of which constitutes a projection which 10 co-operates with an arcuate arrangement of depressions 49 to maintain the ink feed in its desired adjusted position. 5

The employment by me of a plastic, as distinguished from a fluid feeding ink, results in 15 avoidance of the over inking of the ribbon by the mere standing of the device. By employing a plastic, as distinguished from a gravity feeding ink, the time of the setting of the ink is much decreased and the liability to smearing is 20 reduced. I have also found that the regulation of ink feed, as herein illustrated and described, is much more dependable than can be anticipated when a fluid or semi-fluid ink is employed. 25

Having described my invention what I claim 25 as new and desire to secure by Letters Patent is:

1. Mechanism for feeding and inking typewriter ribbons comprising a revolvably mounted roller about which a ribbon is adapted to be passed, a second roller revolvably mounted adjacent said 30 first mentioned roller, an ink reservoir having a recess in the wall thereof, which recess constitutes a portion of the path of rotation of said second roller, a felted lining for said recess and a perforation in the recessed wall of said ink reservoir, said felted lining being punctured opposite said perforation, an ink feed bar pivotally mounted within said ink reservoir and movable to enter and withdraw from the perforation in the wall thereof and the puncture in said felting and 40 means for simultaneously rotating said rollers in opposite directions and oscillating said ink feed bar. 55

2. Mechanism for feeding and inking typewriter ribbons comprising a pair of co-operating 45 rollers around one of which a ribbon is adapted to be led, an ink reservoir, a portion of which lies parallel to and adjacent the path of revolution of one of said rollers, said reservoir having a port therein opposite the roller adjacent thereto, 50 an ink feed bar movably mounted within said reservoir and adapted to enter and withdraw from said port and means for simultaneously rotating said rollers in opposite directions and oscillating said feed bar. 55

3. Mechanism for feeding and inking typewriter ribbons comprising a pair of co-operating rollers around one of which a ribbon is adapted to be led, an ink reservoir, a portion of which lies parallel to and adjacent the path of revolution 60 of one of said rollers, said reservoir having a port therein opposite the roller adjacent thereto, an ink feed bar movably mounted within said reservoir and adapted to enter and withdraw from said port, means for simultaneously rotating 65 said rollers in opposite directions and oscillating said feed bar, and means for adjusting the latitude of oscillation of said feed bar.

4. Mechanism for feeding and inking typewriter ribbons comprising an inking roller, an ink 70 reservoir, a portion of which lies parallel to and adjacent the path of revolution of said roller, said reservoir having a port therein opposite said roller, an ink feed bar movably mounted within said reservoir and adapted to enter and be withdrawn 75

from said port, means for rotating said roller, and means for reciprocating said feed bar.

5. Mechanism for feeding and inking type-writer ribbons comprising an inking roller, an ink reservoir, a portion of which lies parallel to and adjacent the path of revolution of said roller, said reservoir having a port therein opposite said roller, an ink feed bar movably mounted within said reservoir and adapted to enter and be withdrawn from said port, means for rotating said roller, means for reciprocating said feed bar and means for adjusting the latitude of reciprocation of said feed bar.

6. Mechanism for feeding and inking type-writer ribbons comprising an inking roller, an ink reservoir, a portion of which lies parallel to and adjacent the path of revolution of said roller, felting interposed between the adjacent portions 5 of said reservoir and said roller, said reservoir having a port therein opposite said roller and said felting being punctured opposite said port, an ink feed bar movably mounted within said reservoir and adapted to enter and be withdrawn 10 from said port, means for rotating said roller, means for reciprocating said feed bar.

GEORGE S. BRODD.
